M. E. BUTCHER.

ARTICLE HANGER.

APPLICATION FILED AUG. 21, 1915.

1,172,937.

Patented Feb. 22, 1916.

Mary Elizabeth Butcher,

By
Royal E. Burnham, attorney

UNITED STATES PATENT OFFICE.

MARY ELIZABETH BUTCHER, OF CAMBRIDGE, MASSACHUSETTS.

ARTICLE-HANGER.

1,172,937.

Specification of Letters Patent.

Patented Feb. 22, 1916.

Application filed August 21, 1915. Serial No. 46,677.

To all whom it may concern:

Be it known that I, MARY ELIZABETH BUTCHER, a citizen of the United States, residing at Cambridge, in the county of 5 Middlesex and State of Massachusetts, have invented certain new and useful Improvements in Article-Hangers, of which the following is a specification, reference being had therein to the accompanying drawing.

10 This invention provides a hanger of novel form arranged to be hung on closet-doors, inside of closets, on walls, and elsewhere, for supporting garments, footwear, umbrellas, canes, household articles, hand-bags, etc. 15 The main or supporting member of the hanger is a flexible strip, which can be wound or folded into compact form, thus making the article convenient to be taken by travelers for use in state-rooms, sleeping- 20 cars, tents, and other places.

It is an object of the invention to provide an article of this kind in which the article-holding members are arranged in a novel manner, and which can be used either in a 25 horizontal or suspended position.

When read in connection with the description herein, the details of the invention will be apparent from the accompanying drawing, forming part hereof, wherein embodiments of the invention are disclosed, for 30 purposes of illustration.

While the embodiments disclosed now are considered preferable ones, it is to be understood that it is not the intention to be limited necessarily thereto in interpretation of the claims, as it is apparent that changes within the limits of the claims can be made 35 without departing from the nature and spirit of the invention.

40 Like reference-characters refer to corresponding parts in the views of the drawing, of which—

Figure 1 is a view of one form of the invention suspended; Fig. 2 is a view of another form of the invention suspended; Fig. 3 is a view of the form shown by Fig. 2 as is use in a horizontal position; Fig. 4 is a view of still another form of the invention particularly adapted for use in a horizontal 45 position; Fig. 5 is a view of one of the article-supporting members used on the form shown by Fig. 1; Fig. 6 is a view of one of the article-supporting members used on the form shown by Figs. 2 and 3; and Fig. 7 is a view of one of the article-supporting members used on the form shown by Fig. 4.

Referring more particularly to the drawing, 8 designates a comparatively narrow strip of flexible material, such as tape. In all forms herein shown, the strip is provided at one end with a hook 9 arranged for engagement with molding, a fixed hook, or any other suitable part, for suspending the device; and at the other end—the end that is the lower when the device is suspended for use—the strip is provided with a ring 10. The strip 8 carries at suitable intervals article-supporting members arranged to have hung thereon the articles to be taken care of.

In the form shown by Fig. 1, article-supporting members 11 as shown by Fig. 5 are used. Each of these members is made of a length of wire, pointed at one end and bent in that end portion to form a hook 11^a, a shank 11^b extends therefrom, and near the end of the shank the wire is bent substantially at right angles to the shank as a short arm 11^c, which is formed with a head 11^d. The members 11 are attached to the strip 8 each by passing the pointed end through the material from one side at one place and back through the material at another place and then drawing the strip taut, so that the hook 11^a projects from the strip and the member is prevented from becoming disconnected from the strip by the short arm 11^c and the head 11^d. Any desired number of these hooks thus can be placed on the support-strip 8 at intervals to meet the demands to be made upon the device, and while in use 90 the hooks, or any of them, may be removed and attached at different places to meet varying needs.

Each of hooks 12 shown by Fig. 6 and used on the form of the invention shown by Figs. 2 and 3 is made of a length of wire bent upon itself midway of its ends to form a doubled length and then bent to form a hook proper 12^a, from which continues upwardly a shank portion 12^b. In the upper 100 end portion, each strand of wire is bent substantially at right angles to the plane of extension of hook portion 12^a, whereby laterally-extending attaching-arms 12^c constituting a head, are provided. Each of the 105 members 12 is attached to strip 8 by passing through a perforation therein preferably midway between its margins, the arms 12^c preventing the member from passing entirely through the material of the strip and 110 becoming disengaged therefrom. If desired, in order to prevent the hooks from passing

backwardly through the strip 8 and thus becoming detached while the device is loose as while not in use or hung, the material of the strip may be brought together on each 5 side of the arms 12^a and secured by stitching 12^a, whereby loops 12^a enveloping the arms are formed.

In the form of the invention shown by Fig. 4, the strip 8 is passed through the eyes 10 of eye-hooks 13, which are slidable on the strip to any positions desired for suspending the device and for suspending articles thereon.

When the form of the invention shown by Fig. 1 is to be used, it is suspended by engaging its hooks 9 with a fixed support, and articles may be hung on hooks 11 in any desired manner, either by passing loops, such as found on garments and shoes, thereover, 15 or, in the case of those articles that are perforated easily, by passing the pointed ends of the hooks therethrough. The form shown by Figs. 2 and 3 may be suspended and used 20 in a manner similar to that of Fig. 1, except that the ends of the hooks are not sharp enough to perforate articles ordinarily hung on such devices; or it may be hung in a substantially horizontal position, as shown by Fig. 3, by attaching the hook 9 at one end 25 and the ring 10 at the other end to fixed supports, as, for example, to hooks usually found in a closet. When the hangers are suspended in a vertical position, the rings at the lower ends thereof may be used to hold 30 canes, umbrellas, or the like. The form shown by Fig. 4 is designed particularly for hanging in a substantially horizontal position. It may be held in such position by attaching its hook 9 and ring 10 to fixed hooks 35 or other suitable supports, it may be supported at its ends and intermediate its ends 40

by engaging some of its hooks 13 over the edge of such a part as a shelf leaving other of its hooks 13 for holding garments or other articles, the hooks for both purposes 45 being moved along the strip 8 to the positions required, or the strip 8 may be strung over a series of fixed hooks and secured at its ends by the hook 9 and ring 10, leaving all of the hooks 13 dangling and available 50 for the hanging of articles thereon.

Having thus described my invention, what I claim as new, and desire to secure by Letters Patent, is—

1. An article-hanger comprising a narrow 55 strip of flexible material having means of suspension at one end, and an article-supporting member formed of a length of wire bent upon itself intermediate its ends and bent to form a hook proper, a shank extending therefrom, and each strand of wire being bent laterally at the end of the shank to provide an arm, said member being disposed through said strip with its arms holding it thereon. 60

2. An article-hanger comprising a narrow strip of flexible material having means of suspension at one end, and an article-supporting member formed with a hook in one end portion and laterally-extending arms at 70 the other end, said member being disposed through said strip and the material of the strip being secured together at each side of the arms whereby there is formed a loop of the material enveloping the arms. 75

In testimony whereof I affix my signature in presence of two witnesses.

MARY ELIZABETH BUTCHER.
